UNITED STATES PATENT OFFICE.

SAMUEL ZIMMERMAN, OF SENECA, KANSAS.

TOOL.

1,076,732.

Specification of Letters Patent.

Patented Oct. 28, 1913.

Application filed March 15, 1913. Serial No. 754,612.

To all whom it may concern:

Be it known that I, SAMUEL ZIMMERMAN, a citizen of the United States, residing at Seneca, in the county of Nemaha and State 5 of Kansas, have invented certain new and useful Improvements in Tools, of which the following is a specification, reference being had to the accompanying drawings.

This invention relates to new and useful 10 improvements in tools and more particularly to that class adapted for use by piano tuners in perforating the felt hammers to change the tone of a piano.

The object of this invention is the pro- 15 vision of a tool of this character which comprises a pair of pivotally united members having handles provided at one side of the pivotal point and heads provided upon the other side of the pivotal point, one of said 20 heads being capable of removably supporting a plurality of perforating points, while the other of the said heads is adapted to clamp the felt between the heads, holding the same against movement while being per- 25 forated.

Another object of this invention is to im- 30 prove and simplify devices of this character, rendering them comparatively simple and inexpensive to manufacture, reliable and effi- 35 cient in use and readily operated.

With the above and other objects in view, this invention resides in the novel features of 35 construction, formation, combination and arrangement of parts to be hereinafter more 40 fully described, claimed and illustrated in the accompanying drawings, in which—

Figure 1 is a plan view of one part of the 45 tool; Fig. 2 is a plan view of the other part of the tool; Fig. 3 is a side elevation of the 50 tool.

Referring to the accompanying drawings by similar characters of reference throughout the several views, the numeral 10 designates generally my improved tool which 45 consists of a pair of rectangular bars 11 and 12, pivotally united at their inner ends as shown at 13. Handles 14 are formed at the ends of the bars 11 and 12 preferably at their piv- 50 otal connection 13, the said handles being normally forced outwardly by means of the spring 15, which is riveted or otherwise se- 55 cured to the inner side of one handle, for engagement with the confronting inner side of the other handle. A similar spring 16 is

secured to the inner side of the bar 12 for 55 engagement with the adjacent sides of the pins 19, for the purpose of forcing the outer ends of said bars apart and the felt from the pins. A head 17 is formed upon the outer end of the bar 12, and projects equally 60 distant upon the opposite sides thereof, the said head being formed in its outer edge with a plurality of vertical grooves 18 for the reception of the perforating pins 19.

A removable bar 20 formed with grooves 65 21 disposed in registration with the grooves 18 is secured to the head 17 by clamping screws 22, and is adapted to coöperate with the outer edge of the head 17 for the purpose of retaining the perforating pins 19 against 70 the displacement from the grooves 18 and 21. A similar head 23 is formed upon the outer end of the bar 11 and is of a size and shape to correspond with the before mentioned head 17. The outer side of the head 75 23 is provided with a recess 24, while secured to the outer side thereof is a removable end bar 25, retained thereon by clamping screws 26 similar to the before mentioned clamping screws 22. This bar 25 coöperates with the 80 recess 24 in producing a slot for the reception of the pins 19 when the heads are forced together.

The operation of the device is as fol- 85 lows:—The felt to be perforated and which is indicated by the numeral 27 is inserted between the heads 17 and 23 and the handles 14 are drawn together, which forces the perforating pins 19 through the felt, thus perforating the same in the desired manner.

It should be understood in this connection 90 that various minor changes in the specific details of construction can be resorted to within the scope of the appended claim with- 95 out departing from or sacrificing any of the advantages of the invention. It should be further understood in this connection that I am not to be limited to the use of the tool in perforating felt for piano hammers, but may use the device in any other connection 100 to which the various parts thereof will adapt themselves.

Having thus fully described this invention, what I claim as new and desire to protect by Letters Patent is:—

A tool comprising a pair of pivoted han- 105 dle bars, handles formed upon said handle bars at one end thereof, heads formed on the

other ends of said bars, one of said heads being provided with a recess in its outer face and intermediate of its ends, an end bar removably connected to the outer face of said head and adapted to close the recess therein to produce a slot between the head and end bar, and a pin removably mounted in the other of the heads and adapted to project

within said slot, as and for the purpose described. 19

In testimony whereof I hereunto affix my signature in the presence of two witnesses.

SAMUEL ZIMMERMAN.
